PRINTING MACHINE

Walter T. Gollwitzer, Chicago, Ill., assignor to
 Addressograph Company, Wilmington, Del., a
 corporation of Delaware

Application July 23, 1930, Serial No. 469,953

50 Claims. (Cl. 101—58)

This invention relates to printing machines of the kind through which a plurality of printing devices are sequentially passed for use in printing operations. The printing devices may have a printing form thereon for addressing purposes or the like and are introduced into a magazine in the machine, from which they are withdrawn and passed through printing position, after which the printing devices are collected and stored in a suitable manner. These printing devices are stored, passed through the machine, and collected in a predetermined sequence, as for example, alphabetically.

Printing or addressing machines of the foregoing character are used in many commercial enterprises and one typical use is by so-called mail-order houses. It has been found that customers of such houses often buy only certain kinds of merchandise, and it is therefore not profitable to send all customers all of the advertising literature and the like broadcast by such houses. An example of the foregoing is that some customers may buy only boots and shoes, others clothing, still others farm implements, and so on. Because of this, it is customary to address the advertising literature only to customers interested in merchandise of the character described in the particular literature being sent out. When printing machines of the kind to which this invention relates are used for the addressing, a selecting mechanism is provided which may be controlled in many different ways as, for example, by providing tabs, notches or other identifying means on the printing devices engageable by detectors in the printing machine, which determine whether or not a printing device is to be used in an addressing operation, and thus the printing devices for customers who are not to receive literature of the character being sent out are not used in an addressing operation; that is, such printing devices are skipped.

It has been pointed out that certain customers usually buy only certain types of merchandise, and the selecting mechanism may be arranged for control by this purchasing characteristic of the customers, this being known as a primary selection. In addition, the credit rating of the customers varies; that is, some customers have unlimited credit, while others have a high credit rating but limited, still others have a low credit rating, and some customers are dealt with only on a cash basis. It is, therefore, desirable that the selecting mechanism be operable to determine whether or not a printing device is to be used in an addressing operation in accordance with the

credit rating of the customers represented by the printing devices. This latter selection is also a so-called primary selection. It is also desirable to provide what are termed secondary selections; for example, the house may find that it is advantageous to circularize certain customers during the holiday seasons as, for example, at Christmas or Easter. Further, special sale campaigns may be put on from time to time in which it is desirable to circularize only certain customers with certain credit ratings, or customers in certain geographical areas, or the like. It will be readily manifest that the number of combinations of selection that might arise under this secondary selection is very high, and therefore, it is highly advantageous to provide a selecting mechanism which will be so constituted that a very large number of selections may be brought about thereby.

The executive, as for example, a department manager, a sales or advertising manager, or the like, usually determines what customers are to be circularized, but such an executive obviously does not operate the machine nor does he actually set up the machine to bring about the desired selection of printing devices. To avoid incorrect addressing of literature, and the resultant waste, it is desirable that the selecting mechanism be so arranged that the set-up thereof may be readily determined in a positive manner and thus costly errors due to incorrect addressing may be eliminated.

The salient objects of my invention are to provide a novel selecting mechanism for printing machines and the like which provides a large number of primary selections and a vast variety of secondary selections; which is of simple construction and so arranged that it may be easily set up to determine a desired selection; which embodies a signal arrangement operable by the selector mechanism; which embodies a removable part, for example, one in the form of a so-called matrix, that determines the set-up of the selecting mechanism; which employ a matrix of simple inexpensive construction so that a number of matrices may be provided economically, the matrices being differently formed to bring about different selections; and which is so arranged that the selection may be reversed; that is, when the printing devices are once sequentially passed through the machine, certain printing devices are used while others are not, but in my improved device this condition may be readily altered so that the printing devices not used in the first sequential passage are used on the next

- passage, while those used in the first passage are not to be used in the second.
- When advertising literature and the like is addressed, frequently more than one piece is sent to each customer. It is therefore another object of my invention to provide a printing machine wherein a number of repetitious impressions may be made from each printing device passed into printing position so that a number of pieces of literature may be addressed, and an ancillary object is to provide a printing machine wherein these repetitious printing operations are only performed from printing devices which are determined by the selecting mechanism.
- 15 Printing devices of the character used in the machines of the type to which my invention pertains are of restricted size and therefore it is a further object to provide a selecting mechanism which is controllable from portions on the printing device of restricted size, and, therefore, a large number of such portions may be provided on the printing device.
- A selected embodiment of my invention is illustrated in the accompanying drawings wherein
- 20 Fig. 1 is a front elevation of a machine constructed in accordance with my invention;
- 25 Fig. 1a is a fragmental perspective view of a portion of the machine-operation controlling mechanism;
- 30 Fig. 2 is a fragmental side elevational view of the machine illustrated in Fig. 1;
- 35 Fig. 2a is a detail front view of a clutch employed in the machine;
- 40 Fig. 3 is a fragmental sectional view of the operating mechanism looking in from the right hand end of the machine as shown in Fig. 1;
- 45 Fig. 4 is a fragmental elevational view of the operating mechanisms looking in at the rear of the machine;
- 50 Fig. 5 is a fragmental detail view of a shifting mechanism provided in the machine;
- 55 Fig. 6 is a fragmental front elevation, drawn to an enlarged scale;
- 60 Fig. 6a is a sectional view taken transversely through the anvil at printing position.
- Fig. 7 is a view taken substantially on the line 7—7 on Fig. 1;
- Fig. 8 is a sectional view taken substantially on the line 8—8 on Fig. 4;
- 55 Fig. 9 is a fragmental detail view of a portion of the mechanism controlling the platen operation;
- 60 Fig. 10 is a top plan view, drawn to an enlarged scale, of the detecting portion of the selector mechanism;
- 65 Fig. 11 is a view taken substantially on the line 11—11 on Fig. 2a;

- 75 Fig. 13 is a detail view of the feeler or detecting fingers of the selector mechanism;
- 80 Fig. 14 is a fragmental view, similar to Fig. 7, and drawn to an enlarged scale, showing the operating mechanisms as arranged in one position by the selector mechanism;
- 85 Fig. 15 is a perspective view showing the printing device, the detecting fingers and the matrix as arranged to locate the parts in the manner shown in Fig. 14;
- 90 Fig. 16 is a view, similar to Fig. 14, showing the parts in another operating position;
- 95 Fig. 17 is a perspective view, similar to Fig. 15, showing the parts in the position illustrated in Fig. 16;
- 75 Fig. 18 is a view, similar to Figs. 14 and 16,

showing the parts in another operating position;

Fig. 19 is a view showing the matrix and a portion of the selector mechanism control;

Fig. 20 is a view, similar to Fig. 19, showing the selector mechanism in another position;

Fig. 21 is a fragmental view, similar to Fig. 18, showing a portion of the selector mechanism in another operating position;

Fig. 22 is a view, similar to Fig. 21, showing the parts in still another operating position;

Fig. 23 is a perspective view of one of the printing devices; and

Fig. 24 is a perspective view showing the matrix.

While the selecting mechanism of this invention may be used in connection with printing machines of various forms of construction, I have, in the drawings, shown the mechanism in connection with a printing machine embodying a

20 frame 25 composed of suitably joined tubular members. On the shaft 27 of the motor 26, (Fig.

1) carried by the frame 25, is a pulley structure 28. Depending from the bed 29 of the machine

is a bracket 30 and a jack shaft 31 is journaled in 25 bearings in this bracket. On the jack shaft 31

is a pulley arrangement 32 and a belt 33 interconnects the pulley arrangements 28 and 32 to transmit power from the motor 26 to the jack shaft 31.

The main drive shaft 34 of the machine is journaled in suitable bearings such as 35 and rotatably mounted thereon is a spur gear 36 that meshes with a pinion 37 fixed on the jack shaft 31. Fixed to one face of the spur gear 36 is a disc 37' (Figs.

30 2a and 11) surrounded by a clutch housing 38 secured to the shaft 34. Pivottally mounted on the

clutch housing 38 is an arm 39 and a spring 40 is disposed between this arm 39 and a bushing about the shaft 34 to urge said arm away from said

shaft. The arm 39 is substantially arcuate in contour and has a segment 41 thereon, engaged by

40 the teeth 42 on the pin 43. The pin 43 serves as a tumbler and includes a portion engageable in

the notches 45 in the disc 37'. When the pin 43

is seated in one of the notches 45, the disc 37' 45

is connected to the clutch housing 38 and the

shaft 34 is rotated.

Pivottally mounted on the frame 25 is an arm

46 having a nose 47 thereon engageable with a

50 nose 48 on the arm 39. When the nose 47 engages

the nose 48 the arm 39 is held against rotating

movement and therefore the arm 39 tends to wrap

around the shaft 34, and it thus moves toward

said shaft and compresses the spring 40 and also,

through the segment 41, rotates the pin 43 to

move the flat portion 44 into tangential relation

with the periphery of disc 37 and the notches 45

to disconnect disc 37 and the clutch housing 38

which interrupts rotation of the drive shaft 34.

A friction 49 (Fig. 2a) is provided, which is

secured to the gear 36, and this friction bears on the

clutch housing 38 to prevent retroactive move-

ment thereof, which might be caused by the

spring 40, with a resultant reengagement of the

clutch. As soon as the nose 47 is disengaged from

the nose 48, the spring 40 will move the arm 39

outwardly away from the shaft 34 which will

cause the tumbler 43 to move the portion 44 from

the tangential relationship with the notches 45,

and as the disc 37 rotates the pin will reseat in

70 one of the notches to again cause rotation of

shaft 34.

The disengagement of the nose 47 from the

nose 48 is brought about by moving the rod 50

downwardly. As best illustrated in Fig. 2, the

75

rod 50 engages the end of the arm 46 opposite the nose 47, said arm 46 being pivoted on the frame 25 as indicated at 51 (Fig. 2). The rod 50 is connected to the arm 52 of the rocker 53 (Fig. 1a) mounted on the shaft 54 carried by the arm 55 and the bracket 56 on the frame 25 (Fig. 1). A link 58 is attached to the arm 57 of the rocker 53 and also to the foot pedal 59 (Fig. 1). When the foot pedal 59 is moved downwardly the rocker 53 is pivoted on the shaft 54 and the arm 52 therefore moves downwardly to similarly move the rod 50, which is held in an upper position by the spring 60 (Fig. 1a) extended between a portion of the frame 25 and a lug 61 on the arm 52. Also fixed on the shaft 54 is an arm 62 (Fig. 1) having a link 63 connected thereto which is also connected to the foot pedal 64. An arm 65 is fixed on the shaft 54 and has a lug 66 thereon rested on the upper surface of the arm 57 of the rocker 53. By depressing the foot pedal 64 the rod 50 will be moved downwardly and, therefore, the connection between the gear 36 and the shaft 34 is controllable by either the foot pedal 59 or the foot pedal 64. A bracket 67 extends upwardly from the arm 55 and provides a bearing in which a stub shaft 68 is journaled. A disc 69 is eccentrically mounted on the stub shaft 68 and has a handle 70. By gripping the handle 70, the disc 69 may be rotated to move the most eccentric portion thereof into engagement with the arm 52, and thus said arm 52 may be moved downwardly to similarly move the rod 50 for the purpose set forth. By permitting disc 69 to remain in this position the shaft 34 and the gear 36 may be interconnected to cause constant rotation of said shaft. When the disc 69 is so rotated that the least eccentric portion thereof engages the arm 52, the rod 50 is permitted to move into upper or clutch disengaging position. It is therefore apparent that the operation of the main drive shaft 34 may also be controlled by the disc 69.

The various mechanisms in the machine are operated from the main drive shaft 34 and among these mechanisms are those which bring about sequential passage of the printing devices through printing position. The printing devices, indicated by D, are introduced into the magazine 71 (Fig. 6) of the machine. Extending across the machine is a guideway 72 (Fig. 7), having one end arranged below the magazine 71 and the opposite end arranged above the printing device receiving compartment 73 (Fig. 1). Disposed below the guideway 72 is a center bar 74 (Fig. 7) having a plate 75 on the upper edge thereof on which the printing devices D are rested, said plate preferably being of a width equal to the distance between the spacing flanges on the printing devices so that the printing devices neatly fit on said plate. Extending in juxtaposition to the center bar 74 on each side thereof are rails 76 and 76' (Fig. 6a). Mounted inwardly of the rail 76 is the slide bar 77 having driving pawls 78 mounted thereon (Figs. 6 and 7). These driving pawls 78 are urged upwardly by springs 79. At the rear end of the slide bar is a portion providing a shoulder 80 which engages the lowermost of the printing devices in the magazine 71 to move this printing device into the guideway 72, the upper surface of this portion holding the remaining printing devices in the magazine during this forward movement. The printing devices withdrawn from the magazine and passed into the guideway 72 are held against rearward movement by stop pawls 81, (Fig. 6a) since a reciprocating move-

ment is imparted to the slide bar 77 to impart a step-by-step movement to the printing devices. At a predetermined point in the guideway 72 an anvil 82 (Fig. 6a) is provided and the printing devices are moved into position above this anvil, a ribbon R (Fig. 6) being directed over the printing device D above the anvil 82. Any suitable means may be provided for imparting movement to the ribbon R, one such means being disclosed in my co-pending application, Serial No. 467,784, filed July 14, 1930. After passing through printing position, the printing devices are directed to the printing device receiving compartment 73 wherein they are collected.

The slide bar 77, as has been stated, has a reciprocal movement imparted thereto, and this is imparted by the rod 83 (Fig. 6) connected to the lug 84 depending from said slide bar and pivotally connected thereto. The rod 83 is pivotally connected to the upper end of a rocker 85 pivotally mounted on the stub shaft 86 carried by the bracket 30 (Fig. 3) depending from the bed 29. Another rocker 88 is mounted on the stub shaft 86 adjacent the rocker 85. On the rear face of the rocker 88 along the edges thereof are projecting flanges 89 and 90 (Fig. 8) which provide a guideway 91 therebetween. Disposed in the guideway 91 is a roller 92 carried by the crank 93 mounted at the outer end of the shaft 94 supported by the bracket 30 (Fig. 8). On the opposite end of the shaft 94 is a bevel gear 96 which meshes with a bevel gear 97 fixed on the shaft 34. Therefore, when the shaft 34 is rotated movement is imparted through the bevel gears 97 and 96 to the shaft 94 to operate the crank 93 to cause the roller 92 to move back and forth in the guideway 91, and by reason of the throw of the crank 93 a rocking movement is imparted to the rocker 88. On the rocker 88 is a lug 98 which extends past one edge of the rocker 85. Pivotally mounted on a boss 99 on the rocker 85 is a pawl 100 (Fig. 6) having a notch 101 engaging the lug 98 to interconnect the lug 98 and the pawl 100 and, consequently, the rockers 85 and 88. A spring 100' (Fig. 6) extends between pins on pawl 100 and rocker 85 to hold the pawl 100 in this position. It is therefore apparent that, as long as the notch 101 engages the lug 98 and the shaft 34 is rotated, a rocking movement will be imparted to the rocker 85, which rocking movement will be transmitted through the rod 83 to the slide bar 77. Therefore, the printing devices will be withdrawn from the magazine 71 and sequentially passed through the machine.

Pivotedly mounted on the selector bracket 95 at 55 102 (Fig. 6) is an arm 103 which has a pin 104 (Fig. 2) at one end thereof through which the rod 105 is extended, nuts 106 being provided at the upper end of the rod 105, and about said rod, between said nuts and the pin 104, is a spring 107. 60 The lower end of the rod 105 is connected to an arm 108 on the shaft 54 (Fig. 1a). Therefore, when the foot pedal 64 is depressed to cause rotation of the shaft 54, the rod 105 will be moved downwardly compressing the spring 107 which will act to pivot the arm 103 downwardly. The pin 104 bears against the inclined surface of the pin 109, (Fig. 6), extended upwardly from the pawl 100, and this causes the pawl to be pivoted to disengage the notch 101 from the lug 98 to disconnect the rocker 85 from the rocker 88 and, therefore, the movement imparted to the slide bar 77 will be interrupted which will stop the feeding of the printing devices through the machine.

A printing impression is taken through the rib- 75

bon R from the printing device D, disposed above the anvil 82, by a platen P. The platen P is mounted on the outer end of the platen arm 110 and said platen may be of any desired construction, as for example, that disclosed in my co-pending application, Serial No. 467,784, filed July 14, 1930.

The platen arm 110 is pivotally supported on the shaft 111 (Fig. 7) mounted at the rear of the bed of the printing machine. The platen arm includes a depending arm 112 (Figs. 2 and 7) extended below the shaft 111, and at the lower end of arm 112 is a lug 113 (Fig. 16) engageable in the notch 114 of the arm 115 pivotally mounted at 116 10 on a bracket depending from the frame 25. When the platen arm is in upper or non-printing position, as disclosed in Fig. 1, the lug 113 is engaged in the notch 114. However, in a manner to be described hereinafter, the arm 115 is pivoted 15 to retract the notch 114 from engagement with the lug 113 and by reason of the overhanging extent of the arm 110, best disclosed in Figs. 2 and 7, and by reason of the weight of the platen P at the outer end of the arm 110, said arm pivots about 20 the shaft 111 toward the printing device arranged above the anvil 82, it being apparent that the platen moves downwardly by its own weight. Thus, if the operator's hand or other obstruction 25 is in the path of the platen, no injury results as the weight of the platen is insufficient to cause 30 injury. However, just prior to the time the platen is to perform the printing operation means are provided for bringing about connection thereof with the driving means so that a blow of appreciable force is struck by the platen.

The platen is driven from the main drive shaft 34 and eccentrically mounted on this main drive shaft is an eccentric disc 117 (Fig. 3) surrounded by an eccentric bushing 117', which, in turn, is 40 surrounded by the clamp strip 118 retained in position by the clamp portion generally indicated by 119. Formed as a unitary part of the clamp strip 118 is an arm 120 having a block 121 secured thereto, defining a shoulder 122. As the shaft 34 is rotated an oscillatory movement is imparted to the arm 120, and this movement is utilized to impart driving action to the platen arm. Adjacent the lower end of the arm 112 a dog 123 is pivotally mounted and has a nose 124 (Fig. 7) at 45 one end and a shoulder 125 at the other end. A spring 126 extends between the dog 123 and the arm 112 and acts on the dog to urge the shoulder 125 toward the path of the shoulder 122, and this 50 action also urges the nose 124 into engagement with the cam surface 127 on the upper edge of the fixedly mounted arm 128, as shown in Fig. 16. As the platen arm pivots downwardly, in the manner previously described, the nose 124 moves along the cam surface 127 and just prior to the movement of the platen into printing position, the nose 55 124 reaches the end of and drops out of engagement with the cam surface 127, as shown in Fig. 7, and the shoulder 125 moves into the path of and engages the shoulder 122. At this time the arm 120 is moving away from the shaft 34, and, therefore, a driving force is imparted from the block 121 to the dog 123, through the depending arm 112 and platen arm 110, to the platen P, which causes 60 the platen to perform a printing operation. Thus 65 it is manifest that the platen cannot be connected to the driving means therefor until a time just prior to the printing impression and, therefore, the platen falls merely by its own weight and is entirely free, and as the nose 124 cannot disengage the cam surface 127 until the space between 70 75

the platen and the member to receive the impression is so small that there is not sufficient room for foreign objects to be below the platen, it is manifest that driving force cannot be imparted to the platen until all likelihood of injury is obviated.

It is often desirable that more than one impression be taken from the printing devices moved into printing position and to do this it is necessary that the platen be repetitiously operated and that the printing device feeding action be interrupted. I have therefore provided an arrangement which enables such repetitious operation of the platen, and this arrangement includes means which operate to bring about consecutive, 10 duplicate, triplicate, or quadruplicate operation of the platen and, if desired, this means might be arranged to bring about further repetitious actions of the platen, as will be made apparent 15 presently.

A shaft 129 (Fig. 14) is suitably supported on the bracket 30 (Fig. 9) and a plurality of peripherally notched discs are rotatably mounted on said shaft and these discs determine repetitious operation of the platen. These discs are operated 20 by a pawl 130 (Fig. 7) pivotally mounted on the outer end of an arm 131 that has a bearing portion 132 through which the shaft 111 is extended. Depending from the bearing portion 132 is a boss 133 and a spring 134 extends between 25 the frame 25 and the boss 133, and this spring acts to urge the arm 131 upwardly. An adjusting screw 135 is mounted in the arm 131 and has a lock nut 136 thereon. The free end of the adjusting screw 135 engages one edge of the arcuate arm 137 (Fig. 4) that is connected to and extends at right angles from the platen arm 110 and the depending arm 112 and about the shaft 111. When the platen moves downwardly, as previously 30 described, an edge of the arcuate arm 137 engages the screw 135 and pivots the arm 131 downwardly against the action of the spring 134. A spring 138 extends between the pawl 130 and the arm 131 and urges the free end of the pawl into engagement with a shield 139, (Fig. 9) carried 35 by the bracket 30, disposed over the peripherally notched discs mounted on the shaft 129.

In the present instance, where the device is to be arranged for consecutive, duplicate, triplicate, and quadruplicate operation of the platen, three 40 such discs are provided, and these discs are indicated by 140, 141 and 142, and by referring to Fig. 9, it may be seen that the shield 139 is slightly wider than the three discs and the spacing therebetween. The disc 140 is engaged by the pawl 130 45 to bring about duplicate operations of the aggregate width of the platen and in the present construction of the machine this disc 140 has twelve notches in the periphery thereof. The disc 141 brings about triplicate operations of the platen 50 and has eighteen notches in the periphery thereof. The disc 142 brings about the quadruplicate operations of the platen and this disc has twenty-four notches in the periphery thereof.

It has been pointed out that the pawl 130 rests 55 on the shield 139 and, therefore, this shield normally withholds the pawl from engagement with the notches in the discs. When the pawl 130 engages the disc 140, having twelve notches therein, more movement is imparted to the discs than 60 when the pawl engages the disc 142 having twenty-four notches therein; therefore, the portion of the shield aligned with the disc 140 is cut away, as indicated at 143, and this portion is cut away to permit the pawl to engage the disc 140 65 70 75

near the start of downward movement of the pawl and to permit the pawl to continue in engagement during most of its downward movement. The shield 139 is also cut away, as indicated at 5 144, in alignment with the disc 142, but it is apparent that a smaller portion of the shield is cut away in this instance so that the pawl only engages the disc for a short period during its downward movement. Intermediate the cut away 10 portions 143 and 144 the shield is cut away, as indicated at 145, and this cut away portion permits the pawl 130 to engage the disc 141 for a period longer than it engages the disc 142 but in an amount less than it engages the disc 140. 15 The remaining portion 140' of the shield is not cut away and, therefore, when the pawl is aligned with this portion 140' of the shield, it merely rides thereover and does not engage any disc, and this is the arrangement which permits consecutive 20 operation of the platen.

As best shown in Fig. 6, an arm 146 is pivotally mounted on the bracket 95 at 147. This arm 146 includes a reduced portion 148 through which the screw 149 is extended, said screw engaging a reduced portion 150 on the arm 103 at the end thereof opposite the pin 104. The opposite end of the arm 146 extends through an opening 151 (Fig. 7) in the bracket 95 and is disposed below the pin 152 mounted near the upper end of the 25 arm 153 that is pivotally mounted at 154. On the arm 153, below the pivotal mounting 154, is a pin 155. Extended through the discs 140, 141 and 142, are six pins 156 equidistantly and circumferentially spaced in the discs. Since six pins are 30 provided, the discs are notched in multiples of six and the discs have been described as having twelve, eighteen and twenty-four notches in the peripheries thereof. When the machine is arranged for consecutive operation, the pin 155 remains 35 engaged with one of the pins 156, as illustrated, for example, in Fig. 7. A spring 157 extends between the bracket 30 and the arm 153 and acts on said arm to hold the pin 155 in engagement with a pin 156.

When the pawl 130 is moved into alignment 40 with, for example, the disc 140 having twelve notches therein, and said pawl is moved downwardly in the manner described, it engages one of the notches on the disc 140 and rotates the disc 140 one-twelfth of a revolution. This moves 45 the pin 156 that has been engaging the pin 155 from such engagement, and the spring 157 pivots the arm 153 to cause the pin 152 to move downwardly. Downward movement of the pin 152 similarly pivots the engaged end of arm 146 and, therefore, the end of arm 146 bearing the screw 149 moves upwardly. This pivots the arm 103 which causes the bearing portion 104 to move along the inclined portion of the pin 109 to disengage the notch 101 from the lug 98 and to thus disconnect the rocker 85 from the rocker 88 50 which, as previously pointed out, disconnects the printing device feed. The screw 149 is adjustable and, therefore, the amount of movement imparted to the arm 103 may be easily varied. Upon the next operation of the pawl 130, the disc 140 is again moved one-twelfth of a revolution. It has been pointed out that there are six of the pins 156 and that these pins are equidistantly and circumferentially spaced; therefore, when the first one-twelfth of a revolution was imparted to the disc 140, the disc was rotated in an amount sufficient to dispose the pin 155 midway between two of the pins 156. Thus, when the latter one-twelfth of a revolution is imparted to the disc, 55

the succeeding pin 156 is moved into engagement with the pin 155 and this pivots the arm 153 upwardly. A spring 158 (Fig. 6) extends between the arms 146 and 103 and holds the ends of these arms in engagement with each other. 60 Therefore, when the pin 152 moves upwardly, the end of the arm 146 carrying the pin 149 will move downwardly and the spring 158 will act to reposition the arm 103 in the position illustrated in Fig. 6 and thus the rocker 85 will be reconnected to the rocker 88 and the printing device feed will again function. Should the pawl 130 be aligned with the disc 141 and should this pawl be operated under these conditions, it will move over the shield 139 and will engage one of the 65 notches of the disc 141 and will impart to said disc one-eighteenth of a revolution. This will disengage one of the pins 156 from the pin 155, and the printing device feed will be disconnected when downward movement of the pin 152 occurs. 70 However, under this condition, the pin 155 will be disposed one-third of the distance between the pins 156 and thus upon the next operation of the pawl 130 the disc 141 will again be moved one-eighteenth of a revolution and the succeeding pin 156 will not engage the pin 155 and, therefore, the printing device feed will again not operate. However, on the next operation of the pawl 130 the disc 141 will again be moved one-eighteenth of a revolution and during this operation the succeeding pin 156 will engage the pin 155 and, therefore, the printing device feed will again be placed in operation. It is therefore apparent when the pawl 130 is aligned with the disc 140 that the printing device feed is interrupted on alternate operations of the machine and when the pawl 130 is aligned with the disc 141 the printing device feed is interrupted for two consecutive operations of the machine and is not reengaged until the third successive operation. Thus, since twenty-four notches are 75 provided in the disc 142, it is apparent that the disc will be rotated but one-twenty-fourth of a revolution on each operation of the pawl 130; therefore, when a pin 156 is disengaged from the pin 155 the succeeding pin does not engage the pin 155 until the fourth following operation of the pawl 130. As the pawl 130 is operated from the platen operating mechanism and as the pawl, in the above described manner, controls the operation of the printing device feed, it is apparent that the platen will make consecutive, duplicate, triplicate, or quadruplicate operations on the same printing device dependent upon the setting of the pawl 130. 80

To determine the setting of the pawl 130 on the shield 139, I provide the following arrangement: A groove 159 is provided in the shaft 111 through which a rod 160 (Figs. 4 and 14) is extended. One end of the rod 160 is connected to the bearing portion 132 (Fig. 14) and the other end is mounted in the bifurcation 162 in the lever 163 (Fig. 5). The arm 163 is fixed on a shaft 164 (Fig. 2) that is supported at the rear edge of the bed 29. A handle structure 165 is connected to the shaft 164 and is movable into registration with suitable indices on the upper surface of the bed 29 which indicate the setting, locking means of approved form being 85 provided to retain the handle in registration with different ones of the indices. As best illustrated in Fig. 9, suitable spring washers 166 are disposed between the discs 140, 141 and 142, and these spring washers exert sufficient tension on 90

the discs to prevent turning thereof other than that caused by the pawl 130.

All of the printing devices D passed through the machine are not always used in a printing operation, and this is determined by a selector mechanism. This selector mechanism controls the disengagement of the notch 114 in the arm 115 from the lug 113 and, therefore, the operation of the platen is regulated by the selector mechanism. The selector mechanism in the present device is operated from the shaft 34 and includes feeler or detecting fingers which move into engagement with one side edge of the printing device that is disposed in a position just prior to printing position, and this prior position will be known hereinafter as the selecting position. To bring about the selection in the desired manner, identifying means are provided on the printing devices and in the illustrated embodiment 20 of the invention the edges of the printing devices to be engaged by the feeler fingers are notched in a predetermined manner, the number of notch positions and the number of the feeler fingers corresponding. The movement of the feeler fingers into the notches, or engagement of the feeler fingers with the edge of the printing device where no notches are provided, determine the selection; that is, determines whether or not the printing device in selecting position is to be used in a printing operation.

A printing device of the character used in this machine is illustrated in detail in Fig. 23, and along the edge thereof, which is disposed toward the front of the machine when the printing device is passed therethrough, a plurality of notches, such as 167, may be provided, the possible positions for these notches being illustrated by dotted lines in Fig. 23, and in the present device provision is made for twenty-four notches, the machine being constructed to operate on a printing device provided with that number, but it is to be understood that a greater or less number of notch positions might be provided without departing from the purview of my invention, the machine, of course, being correspondingly changed to care for such variation in the number of notch positions.

Each of the notches 167 formed at the side edge of the printing device D provides what is known as a primary selection. If, for example, the machine is to be used by a mail-order house, one of these notches may indicate customers who customarily buy boots and shoes; another of the notches may indicate customers who customarily buy clothing, and another notch may indicate customers who customarily buy farm implements. From this, it is believed apparent that each notch may be used to indicate certain purchasing characteristics. Certain of these notches, however, 50 may be used to indicate the credit rating of the customers. For example, the last four notches of the printing device, illustrated in Fig. 23, may represent the four credit ratings of the house. Each printing device is notched at the time it is made up in accordance with the foregoing and these provide the primary selections and if, for example, it is desired to send advertising literature to a group of customers who customarily buy boots and shoes, and at the same time it is desired to send advertising literature to customers who customarily buy clothing, while at the same time it is desired to send this literature only to customers having credit ratings under the two better classifications, the selector mechanism is so arranged that the platen operates only on a

printing device having notches representing customers who buy boots and shoes and customers who buy clothing, and which customers have credit ratings under the two better classifications. This is brought about by providing an arrangement which includes a head carrying feeling or detecting fingers, the total number of these fingers equaling the total number of notches that may be provided in the printing device.

Such detecting fingers are illustrated in plan 10 in Fig. 10 and in transverse section in Fig. 14. These feeling or detecting fingers are indicated by 168 and, in the present instance, are twenty-four in number, since the printing devices may be notched at twenty-four different places. These 15 fingers are mounted in a suitable head supported on arms 169 (Fig. 14) pivotally mounted on the shaft 170 fixed in a bearing in the bracket 95 depending from the bed 29. The arms 169 carry a section having a block 171 mounted on the 20 upper edge thereof, a stop plate 172 extending along the front edge of said block. A plurality of spaced rib members 173 are defined by slotting the block 171. The detecting fingers 168 are disposed in the spaces between the rib members 173 25 and include, adjacent one of the ends thereof, hook portions 174 that embrace a pin 175 carried by the rib members and the fingers pivot about this pin. In the upper surface of the fingers 168 are notches 176 engaging a pin 177 30 extending along the upper edge of and carried by the rib members 173. Hair springs 178 are anchored to a pin 179, carried by the rib members 173, and to the block 171 and bear against projections on the lower edges of the fingers 35 168 to tend to pivot the fingers about the pin 175, this pivoting movement being limited by engagement of the notches 176 with the pin 177. Each of the fingers may be pivoted against the 40 action of the springs 178 to permit disengagement of the hook portion 174 thereof from the pin 175 to permit removal of the finger.

It has been pointed out that it is desirable to provide a selector mechanism which may be expeditiously set up and one which is controlled by a removable part in the form of a matrix. Such a matrix is illustrated in Fig. 24 and is indicated by M. In this matrix a plurality of openings are formed which are disposed in rows, the openings in the uppermost row being indicated by 180 while the openings in the lowermost row are indicated by 181. Each of the openings 180 is aligned with an opening 181. The openings 180 and 181 are equidistantly spaced apart and the number of these openings corresponds to the possible number of notches 167 and fingers 168. When such a matrix is manufactured all of these openings are formed.

The matrix M is the part which determines the selection, and this is brought about by plugging 60 certain of the openings 180 or 181. For example, if literature is to be addressed in the manner previously described, to predetermined groups of customers, having certain credit ratings, the openings 181 in the matrix corresponding to the 65 notches in the printing devices for these predetermined groups and credit ratings are plugged, as indicated at 181', under certain conditions of operation of the machine, all of the other openings in the matrix being left open. Therefore, in the present instance, the openings 181 in the matrix which correspond to the customers who customarily buy boots and shoes, and who customarily buy clothing are closed and, in addition, there are plugged openings only for 70 75

such customers as have credit ratings falling within the two better classifications. Thus all printing devices notched in the above manner will be used in a printing operation and this will be true even though the printing devices have other notches therein, for manifestly each customer may buy many different kinds of merchandise. But a printing device not notched in the above manner will not be used in a printing operation as will be made apparent.

A matrix constructed in the above manner is introduced into the machine, a head 182 being provided to receive the matrix. This head 182 has spaced grooves therein into which the side edges of the matrix are fitted. The head 182 is pivotally mounted on the arms 169 at 183 and includes a projection 184. A spring 185 extends between the projection 184 and a pin on one of the arms 169, which spring urges the head 182 toward the tail portions of the fingers 168. On the head 182 is a plate 186 (Figs. 7 and 21) having a pin 187 projecting from one end thereof. A bell-crank lever, generally indicated by 188, is pivotally mounted on the shaft 170 and one end of the arm 189 of the bell-crank lever 188 bears against the pin 187. The free end of the arm 190 of the bell-crank lever 188 carries a roller 191 that bears against the cam 192 fixed on the shaft 34.

A horizontally disposed arm 193 has one end thereof pivotally mounted on the shaft 170 and adjacent this pivotal mounting there is an upwardly extending lug 194 (Fig. 7) on which a lever 195 is pivotally mounted. The lever 195 has a notch 196 therein into which a pin 197 on the arm 169 is extended. Pivotally mounted on the arm 193 adjacent the lug 194 is an arm 198 having a notch 199 therein into which the pointed end 200 of the lever 195 is extended, a spring 201 extending between the lug 194 and the arm 198 to urge the arm toward the lug. Since the lever 195 is pivotally attached to the lug 194 on the arm 193 and as the notch 196 in said lever engages a pin on said arm 169 it is apparent that the arms 193 and 169 are interconnected to move as a unit about the shaft 170. When it is desired to disconnect the arms 169 from the arm 193 the lever is pivoted to disengage the notch 196 from the pin 197 and the pointed end 200 is simultaneously disengaged from the notch 199 and the lever 195 is preferably moved sufficiently to permit the spring 201 to move the upper end of the arm 193 below the adjacent end of the lever 195 and thus the lever is held in a position to disengage the notch 196 from the pin 197. In this manner the selecting mechanism is manually rendered inoperative.

A cam plate 202 has a cam surface 203 thereon which engages the pin 197, and this holds the arm 193 in the position illustrated in Fig. 14 to permit operation of the platen even though the selector mechanism is in inoperative position, for otherwise platen operation is prevented when the selector is rendered inoperative.

On the shaft 34 there is an eccentrically mounted disc 204 (Figs. 7 and 14) and when the shaft 34 is rotated the most eccentric portions of the disc move into engagement with the roller 205 on the arm 193 and thus the end of the arm 193 remote from the shaft 170 will be pivoted downwardly about said shaft. This will pivot the arms 169 toward the printing plate D in selecting position, when the arms 169 are connected to the arm 193. At this same time, the cam 192 (Fig. 7) acts on the roller 191 to operate the bell-crank

188 to move the arm 189 thereof in a direction away from the printing device in selecting position and this cam holds the head 182 in a predetermined position when the arms 169 are pivoted, as above described, said head pivoting against the action of the spring 185. Therefore, the tail portions of the fingers 168 will be entirely disengaged from the matrix M, as illustrated in Fig. 21. The arms 169 will pivot toward the printing device in an amount sufficient to engage the forward ends of the fingers 168 with the notched edge of the printing device D in selecting position. The fingers which engage unnotched portions of this edge will be pivoted against the action of the springs 178 so that the tail portions thereof will be disposed below the plane of the pin 206, carried by the head 182 forwardly of the matrix M. The fingers 168 which move into notches in the printing device will be positioned with the tail portions thereof above the plane of the pin 206. As best illustrated in Fig. 12, the openings 189 are disposed above the plane of the pin 206 while the openings 181 are disposed below this plane. As soon as the less eccentric portions of the disc 204 move into engagement with the roller 205 the spring 207, extended between the bracket 30 and the arm 193, will move the arm 193 upwardly about the shaft 170, and at this same time the cam 192 will act on the roller 191 to permit the bell-crank 188 to disengage the arm 189 from pin 187. The arms 169 will move away from the printing device in selecting position, and the head 182 will move toward the fingers 168. As pointed out, the tail portions of some of the fingers 168 will be above the pin 206 while others will be therebelow. Thus, as the head 182 carrying the matrix M moves toward these tail portions, the tail portions below the pin 206 will pass into the openings 181 in the matrix while the tail portions above the pin 206 will move toward the openings 180. If the printing device in selecting position is notched in the above described manner the tail portions of the fingers which engaged notches in the printing device will pass through openings 180 while the tail portions of the other fingers will pass through openings 181. However, if the printing device is not notched in the manner described the tail portions of the fingers aligned with the plugged openings will be disposed below the pin 206 and will engage the plugs in the openings and therefore none of the tail portions will pass through openings in the matrix. The passage of the tail portions through the openings in the matrix or the prevention of this passage by engagement of the tail portions with plugs determines the selection as will be explained.

On the forward face of the head 182 there is a plate 208 which has at the lower end thereof an angularly extending tail portion 209. Carried by the bracket 95 is a plate 210 having a tapered upper edge including surfaces 211 and 212 on opposite sides of a notch 213 in said edge. As the shaft 34 continues to rotate, the disc 204 will entirely disengage the roller 205 and, therefore, the spring 207 will move the arm 193 and, consequently the arms 169, about the shaft 170 in a direction away from the printing device in selecting position. The head 182 is carried by the arms 169 and is urged toward the fingers by the spring 185, the action of this spring being limited by the engagement of the tail portions of the fingers 168 with the wall of the recess 214 behind the openings in the matrix M. Thus the relative

position between the arms 169 and the head 182 will be definitely determined and as the arms 169 continue movement caused by the spring 207 the tail portion 209 on the plate 208 will engage the surface 211 and will stop the various parts in a definite position, shown in Fig. 14. Forwardly of the roller 205 the arm 193 is provided with an upwardly extending portion 215 and on this portion 215 is a triangular lug 216 having the apex 217 thereof extended in a direction away from the shaft 34. It has been pointed out that the arm 115 is pivotally mounted at 116. Also mounted at 116 is an upwardly extending arm 218 which is pivotal about the mounting 116 and connected to the arm 218, to be movable therewith, is an arm 219 (Figs. 7 and 14), a spring 220 connecting the arms 115 and 219, and a stop 221 is provided on the arm 115 to limit the action of the spring 220. Another spring 222 is connected to the arm 115 and urges this arm upwardly to engage the notch 114 with the lug 113 as shown in Fig. 16. On the edge of the arm 218 disposed toward the shaft 34 there is a V-shaped notch 223, and the edge is tapered adjacent the free end, as indicated at 224, to define a point 225 in alignment with the surface 226 of the arm 218. When the tail portion 209 is rested in the notch 213 the platen arm 110 is locked in upper position, and the nose 217 is disposed along the surface 224 as shown in Fig. 16.

Prior to the time the parts assume the position shown in Fig. 14 the spring 207 will be pivoting the arm 193 upwardly and the arms 169 downwardly, and this movement will continue until the tail portion 209 seats on the surface 211 whereupon movement of the arm 193 will be interrupted. When the arm 193 is stopped by the engagement of tail 209 with surface 211 the nose 217 will be disposed in position to engage the point 225 which will hold the arm 218 in the position illustrated in Fig. 14. The spring 220 is heavier than the spring 222 and consequently when the nose 217 engages the point 225, the spring 220 will overcome the action of the spring 222 and the arms 218 and 219 will move as a unit to move the arm 115 into the position shown in Fig. 14 whereat the notch 114 is disengaged from the lug 113 and, therefore the platen P may operate. In Fig. 15, the manner in which the tail portions of the fingers 168 pass through the openings in the matrix M into the recess 214 is disclosed and, when the fingers move in this manner, the platen is operated under the foregoing conditions.

The just described operation occurs when the printing device in selecting position is notched in a manner similar to that in which the openings 181 in the matrix M are plugged. However, should the printing device in selecting position not be notched in the manner similar to that in which the matrix is plugged, the tail portions of the fingers not entering notches in the printing device will be aligned with openings 181 which are plugged as at 181'. Therefore, the tail portions of the fingers will be prevented from passing into the recess 214 and the head 182 will not pivot toward the fingers as far as it pivots when the tail portions of the fingers enter the recess 214 and therefore the tail portion 209 will not move sufficiently to be aligned with the surface 211 but will be aligned with the end of the notch 213 adjacent the surface 211. It is apparent that the lower wall of the notch 213 is in a plane lower than the surface 211 and, therefore, the arm 193 will be permitted to pivot about the shaft 170 slightly more than when the tail portion 209 en-

gages the surface 211. Thus, in place of the nose 217 engaging the point 225, said nose will clear said point and one of the sides of the triangular lug 216 will rest on the surface 224, as illustrated in Fig. 16.

It has been pointed out that rotation of the shaft 34 may be brought about by depressing either of the foot pedals 59 or 64 or by properly locating the disc 69. Each complete revolution of the shaft 34 brings about one complete operation of the machine. Assuming that a printing device of the character which brings about operation in the manner shown in Fig. 14 has just moved into printing position, the operation of the machine will be as follows when the pawl 130 is arranged to bring about consecutive operation of the platen. At the start of a revolution of the shaft 34 the eccentric 117 will start to move the arm 120 which will so move that the hook portion 227 (Fig. 3) thereof will disengage the bearing portion 228 of the support for the dog 123, and by reason of the fact that the printing device, now in printing position, will have previously been in selecting position, the lug 113 will be disengaged from the notch 114 since the arm 115 will have been pivoted downwardly. Therefore, the platen arm 110 will be free to fall by its own weight until the shoulder 125 engages the shoulder 122 to perform the printing operation. During the time this is occurring the eccentric disc 204 will move into engagement with the roller 205 and will operate the selector mechanism in the manner described, the selector mechanism engaging the printing device in selecting position to determine whether or not this printing device is to be used in a printing operation. Immediately after the platen has performed a printing operation the nose 227 will engage the bearing portion 228 and the arm 120 will be moved toward the front of the machine and, therefore, the platen arm will be moved back into upper or non-printing position by the engagement of the hook portion with the bearing portion.

If, for example, a printing device of the character which arranges the mechanisms as disclosed in Fig. 16 has been in selecting position the arm 115 will be disposed in an upper position whereby the lug 113 will engage in the notch 114. Immediately after the printing operation of the platen P the printing device feed will operate to move the printing devices so that the printing device that has been in printing position will be moved therefrom while the printing device which has been in selecting position will move into printing position. If this printing device is not to be used in a printing operation the platen arm will be prevented from moving downwardly by the engagement of the flattened portion on the lug 113 with the rear edge of the notch 114, when the shaft 34 begins its next complete revolution.

When the device is arranged as shown in Fig. 14 the printing impression will be made during the first 180° of revolution of the shaft 34, and the selector mechanism will engage the printing device in selecting position during the same period and determine the setting of the device for the next revolution of the shaft 34. During the last 180° revolution of the shaft 34 the platen arm will be returned to upper position and the selector mechanisms will lock the parts controlled thereby in the determined position, and also during this last 180° of revolution the printing device feed will operate to advance the printing devices.

The foregoing is the manner of operation when

the machine is arranged for consecutive printing. However, when the machine is arranged, for example, for duplicate printing, it is manifest that a somewhat different operation will occur.

5 When the machine is arranged for duplication, the pawl 130 will be aligned with the disc 140 and during the first operation of the platen arm, the pawl 130 will be moved downwardly to turn the disc 140 one-twelfth of a revolution. Therefore, one of the pins 155 will be moved from engagement with the pin 155 and the arm 153 will be pivoted by the spring 157. Adjacent the lower end of the arm 153 is a shoulder 229 and on the arm 193 is a pin 230. When the arm 153 is moved 10 by the spring 157, the rear edge of said arm engages the pin 230 and when the eccentric disc 204 moves the arm 193 downwardly the shoulder 229 will move in and engage a flat portion on the pin 230, and thus the arm 193 will be held in a downward position with the fingers 168 engaging the printing device in selecting position. It has been pointed out that the printing device feed is rendered inoperative when the pin 155 is disengaged, and since the arm 193 will be locked in a downward position, it is manifest that the selector mechanism is simultaneously rendered inoperative. When the arm 193 is locked in this downward position, the nose 217 is moved into engagement with the surface 226, as illustrated 15 in Fig. 7, and this has the same effect as the engagement of the nose 217 with the point 225 which is to cause the arm 115 to be pivoted downwardly whereby the notch 114 is disengaged from the lug 113. Consequently, the platen P will be rendered operative and will continue to operate 20 so long as the nose 217 engages the surface 226. The arm 193 will be held in this downward position until the succeeding pin 156 engages the pin 155 at which time the shoulder 229 will disengage 25 pin 230 and the selector mechanism will operate in the manner previously described. When the machine is set for duplication, this engagement of the pin 155 by the succeeding pin 156 will occur during the first 180° of revolution of the shaft 34, and when the machine is set for triplicate or quadruplicate impressions this engagement will occur 30 during the first 180° revolution of the shaft 34 for the last of the triplicate or quadruplicate 35 operations of the platen.

In the foregoing description the machine was arranged to print when the printing device in selecting position was notched in a manner identical with the arrangement of plugged holes 181' 40 in the matrix M. In order that the operation opposite to the foregoing may be readily brought about, I have provided the following arrangement: In Figs. 19 and 20 the matrix M is shown. The matrix M, illustrated in Fig. 19, is that which 45 is used to bring about the above operation of the machine. In the lower edge of this matrix there is a notch 231 spaced in a predetermined amount from the side edge 232 of the matrix. The matrix, illustrated in Fig. 20, is that which 50 is used to bring about operation opposite to that above described and herein a notch 233 is provided in the lower edge which is spaced from the side edge 232 of the matrix in an amount less than the spacing of the notch 231. This arrangement is utilized in the following manner: The plate 208 has a slot 234 therein. A screw 235 is extended through this slot into the tail 55 236 depending from head 182. A screw 237 is secured in plate 208 and is extended through a slot 238 in tail 236. A pin 239 is secured to tail 236 and a spring 240 extends between this pin and screw 237 to urge the plate 208 upwardly. Rotatably mounted in the head 182 is a pin 243 having a collar 244 thereon which rests against the inner face of the plate 208 adjacent the upper edge thereof. Outwardly of the collar 244 is a reduced portion 245 which has two flat portions 246 and 247 thereon, and the portion 245 is aligned with the upper edge of the plate 208 and said plate is urged into abutment therewith. Outwardly of the portion 245 a knob 249 is provided on the pin 243 and at diametrically opposed positions on the knob suitably located indicia is provided, for example, the words "Print" and "Skip". When the device is arranged as shown 10 in Fig. 14 the knob 249 is disposed in what may be termed the "Print" position since the device, as disclosed in this figure and in Fig. 16, is arranged to print when a printing device in selecting position is notched in a manner similar to 15 that in which the openings 181 are plugged in the matrix M. This is determined by the engagement of the upper edge of the plate 208 with the surface 246, which is disposed close to the center line of the pin 243. However, if the pin 243 is rotated by gripping the knob 249 to move the surface 247 into engagement with the upper end of the plate 208 the device will be arranged in a somewhat different manner as the surface 247, which will then be engaged with the upper 20 end of the plate 208, is more remote from the center line of the pin 243 than the surface 246. When the device is arranged in this latter manner the extent of the plate 208 from the head 182 is greater than the extent 25 of the plate 208 from the head when the upper edge of said plate 208 engages the surface 246. It will be remembered that in the device as disclosed in Figs. 14 and 16, the platen was permitted to print when the tail portions of the fingers 168 30 moved through openings in the matrix into the recess 214 and that the platen was held against a printing operation when the tail portions of the fingers engaged the face of the matrix. As described, the printing operation was brought about 35 when the tail portion 209 seated on the surface 211. The angular relation between the head 182 and the arms 169 will be determined by whether or not the tails of the fingers 168 move 40 through the openings in the matrix. Now when the device is arranged as shown in Figs. 14 and 16 and the tail 209 is rested on the surface 211, the device will print. But when the device is arranged as shown in Fig. 18, the tail portion 209 45 extends from the head 182 in a greater amount than the extent of said tail portion when the device is arranged as shown in Fig. 14. Consequently, when the tail portion 209 seats on the surface 211, the position of the arm 193 will be varied and the end thereof carrying the lug 216 will not move upwardly in an amount as great as that in which it moved when the tail portion 209 was arranged as shown in Fig. 14. Therefore when the surface 211 is engaged by the tail portion 209 when arranged as shown in 50 Fig. 18, the nose 217 will be located along the edge of the notch 223 extending from the point 225 as shown in Fig. 18, and in this position the arm 115 will be so disposed that the lug 113 will be engaged in the notch 114 and consequently the platen will be held against a printing operation. However, when the tail portions of the fingers 168 engage the face of the matrix and fail to move into the recess 214, the tail portion 209 55 will seat in the notch 213 and this will permit 60 65 70 75

75

the end of the arm 193, carrying the lug 116, to move upwardly in an amount greater than this end of the arm moved when the tail portion 209 seated on the surface 211 with the result 5 that the nose 217 will move into alignment with the point 225 whereupon the arm 115 will be pivoted, as previously described, to disengage the notch 114 from the lug 113 and consequently the platen will perform a printing operation.

10 Attention is called to the fact that identical matrices are employed in these two conditions with the exception of the difference in location of the notches 231 and 233, and this is dependent upon the following arrangement: On the inner 15 end of the pin 243 there is an eccentrically positioned pin 250. When the machine is arranged for operation as shown in Figs. 14 and 16, with the upper end of plate 208 engaging surface 246, the pin 250 is disposed as shown in Fig. 19.

20 Therefore, when a matrix M having a slot positioned as the slot 231 is slipped into the head 182, said slot will pass over the pin 250. However, if a matrix having a notch positioned as the notch 233 is fitted into the head 182 it will be impossible to properly position the matrix when the pin 250 is arranged as shown in Fig. 19 as the slot and pin will not be aligned. But when the pin 250 is positioned as shown in Fig. 20 then a matrix with the notch positioned as the notch 233 may be 25 fitted into the head 182 and under this condition the upper end of plate 208 will engage the surface 247. It will thus be seen that even though the matrices having the openings therein plugged in an identical manner are used it will be impossible to perform incorrect printing operations 30 which might result if the matrices were arranged oppositely, this, of course, also bringing about the above reverse operation. By this opposite arrangement it is meant that the openings 180 35 which were open in the above description would be plugged while the plugged openings would be left open.

40 Operation of the machine is often brought about by arranging the disc 69 in the manner which will cause continuous rotation of the shaft 34. Under these conditions it is often desirable to provide a suitable signal to indicate when a printing device is being skipped or when a printing device is being used in a printing operation and such 45 arrangement might also be utilized when the machine is being operated by the foot pedals 59 or 64. In this machine I have provided an audible signal in the form of a bell, and this bell is operated in the following manner: In the machine, 50 as previously described, the plugging of the openings in the matrices was such that the plugs were flush with the face of the matrix. However, when it is desired to utilize the audible signal the plugs in the matrix are arranged to extend above 55 the face thereof. The audible signal may be arranged either to operate when a printing device is to be skipped or when a printing device is used in a printing operation.

60 If the machine is arranged as shown in Figs. 14 and 16 and the audible signal is to be operated when a printing device is to be skipped, the plugging of the openings in the matrix will be such that the plugs will extend for a short distance above the face of the matrix as, by way of example, for one-thirty-second of an inch. It has been pointed out that all the parts of the selecting mechanism pivot about the shaft 170. When a matrix with flush plugs is used, the tail 70 portion 209 operates between the surface 211 and

the notch 213, but when a matrix with extended plugs is used, the tail portion 209 operates between the surface 212 and the notch 213, as the engagement of the tail portions of the pins 168 with the extended plugs changes the radii of the various paths of movement of the various parts, carried by the arms 169, about the shaft 170. When the device is used with a matrix having flush plugs, the tail portion 209 moves between the surface 211 and the end of the notch 213 adjacent thereto. When the device is used with a matrix having extending plugs therein, the tail portion 209 operates between the surface 212 and the end of the notch 213 adjacent this surface. When a matrix with extended plugs is arranged 10 in the head 182 and the machine is arranged, as disclosed in Figs. 14 and 16, and the selector mechanisms operate as disclosed in Fig. 16 to engage the face of the matrix, which will cause a plate to be skipped, the tail portions of the fingers 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

The tail portion 209 has the portion 251 which is aligned with the extent of the plate 208, and it is this portion 251 which causes operation of the bell. Pivotally mounted on the arm 210 at 252 is a dog 253 that includes a toe portion 254 that normally extends above the surface 212, as illustrated in Fig. 21. The dog 253 also includes an arm 255 having a shoulder 256 thereon, and when the audible signal is inoperative the latch portion 257, on the arm 258 of the bell crank 259, rests on the shoulder 256. The bell crank 259 is pivotally mounted on the shaft 170, as best illustrated in Fig. 22. A spring 261 extends between the arm 258 of the bell crank and the bracket 95 and urges arm 258 downwardly. A spring 260 extends between the bracket 95 and the arm 255 and urges the arm 255 toward the latch 257 to hold the shoulder 256 in engagement with said latch. When the tail portion 209 is seated in the manner last described, the tail portion 251 engages the toe portion 254 and pivots the dog 253 about the pivotal mounting 252 thereof to disengage the shoulder 256 from the latch 257 and the spring 261 pivots the arm 258 of the bell crank 259 downwardly. On the arm 262 of the bell crank 259 a yieldable arm 263 is secured, at the lower end of which there is a knocker 264, which, when the arm 258 is pivoted downwardly strikes the bell 265 to produce an audible signal, said bell being supported on the depending boss 266 and thus an audible signal will be produced each time a printing device is skipped. An adjusting screw 267 extends through the arm 262 and engages a depending boss 268 on the arm 193, and when said arm 193 is pivoted to move the fingers 168 toward the printing device in selecting position this boss 268 engages the pin 267 and pivots the bell crank 259 to cause reengagement of the latch 257 with the shoulder 256.

Under certain conditions it is desirable to produce an audible signal when an impression is taken from a printing device, rather than when a printing device is skipped, and to do this the holes in the matrix are plugged with plugs that are extended above the face of the matrix in an amount greater than that above described, for example, one-sixteenth of an inch, and the parts are arranged as illustrated in Fig. 22. Therefore, when the tail portions of the pins 168 engage one of the plugs, the parts will be so pivoted about the shaft 170 that the tail por-

tion 209 will seat on the surface 212 and the tail portion 209 will engage and move the dog 253 in a manner set forth to cause the knocker 264 to strike the bell 265 to produce an audible signal.

In the foregoing description I have set forth typical secondary selections and it has been pointed out that these secondary selections are brought about by plugging certain of the holes 181 in the matrix M. This plugging of the holes 181 causes the tail portions of the finger 168 to determine movement of the head 182 to position the tail portion 209 so that the platen operation will be controlled in the manner previously described. The foregoing, however, is not to be taken as even a preferred manner of using this device, as there are a vast variety of secondary selections that may be used. When the device is arranged in the manner above described, it is immaterial whether or not notches, other than those of the particular secondary selection, are provided in the printing device. This is very advantageous for, manifestly, the same customer might, for example, buy boots and shoes, clothing, and farm implements. When the machine is set up in the above described manner it will be necessary that the printing devices be notched for both of the better classifications of credit. This would entail the provision of an extra notch in each printing device and if a particular customer had a credit rating of the better classification, it would be necessary, under this circumstance, to provide four notches. It is to be noted, however, that the above description is only intended to be an illustrative use of the invention and is not the only one that might be used. Other selections will be readily apparent to anyone skilled in the art, and these selections may be determined by plugging either the holes 180 or the holes 181 in the matrix to bring about the selection, the holes in the matrix being plugged to correspond to the notches of the selections desired or these holes may be left open and the remaining holes plugged.

In the foregoing description I have set forth a typical use of the invention in a mail-order house, but it is to be understood that the invention is not limited to such a use as it may be very advantageously employed by wholesale institutions, insurance companies, publishers of magazines and other periodicals and in many other different types of enterprises.

In the above description the invention has been set forth as used in addressing operations but the selector mechanism, above described, may be very advantageously employed when the machine is used for listing purposes, and a lister of the character which may be very advantageously used in connection with this machine is described and claimed in my co-pending application, Serial No. 467,783, filed July 14, 1930, now Patent No. 1,937,145, patented November 28, 1933.

In the printing machine above described a platen is provided which is operated in a manner which eliminates the likelihood of injury by reason of the fact that pressure is not applied to the platen until just prior to the time the impression is to be made thereby. This arrangement not only eliminates the likelihood of injury to an operator but also eliminates the likelihood of injury to the machine. In addition, I have provided a machine which may be easily controlled and which may be readily arranged for continuous operation or one which may be operated in a step-by-step manner by utilizing the

foot pedals, it of course being understood that, if desired, either of the foot pedals might be manually held depressed which would also bring about continuous operation. It is also apparent that substantially all of the operating mechanisms are arranged below the bed of the machine and that these parts are arranged in a very compact manner, the advantage of which will be readily apparent to anyone skilled in the art. The machine is also provided with an arrangement whereby consecutive, duplicate or other multiple operations of the platen may be readily brought about, and it is manifest that the adjustment of these parts may be accomplished in a very easy manner.

While the above are all advantageous features, the major feature of my improved and novel machine is the selector mechanism which provides a large number of primary selections and a vast variety of secondary selections. The selection is controlled by a removable part in the form of a simple matrix which may be economically manufactured and which may be readily arranged to bring about the desired selections. It is also apparent that the machine is arranged in such a manner that only desired printing operations will be performed, and such that a matrix which will bring about a selection opposite to that desired cannot be installed in the machine.

While I have illustrated and described a selected embodiment of my invention, it is to be understood that this is capable of variation and modification and I, therefore, do not wish to be limited to the precise details set forth but desire to avail myself of the purview of the invention as set forth in the following claims.

I claim:

1. In a printing machine embodying a platen and means sequentially moving printing devices relative to the platen, the combination of a selector mechanism for controlling the operation of the platen, said selector mechanism including a removable part and detecting members engageable with the printing devices and subsequently engageable with said removable part after disengagement from the printing devices.

2. In a printing machine embodying a platen and means sequentially moving printing devices relative to the platen, the combination of a selector mechanism for controlling operation of the platen, said selector mechanism including a removable part, detecting members cooperating with said removable part, and means for successively moving said detecting members into engagement with each of the printing devices and then into engagement with the removable part subsequent to disengagement of the detecting members from the printing devices.

3. In a printing machine embodying a platen and means sequentially moving printing devices relative to the platen, the combination of a selector mechanism for controlling operation of the platen, said selector mechanism including a removable part, detecting members cooperating with said removable part, means for supporting said removable part, means for supporting said detecting members, and means for successively separating said detecting members and said removable part and for moving said detecting members into engagement with a printing device and for then moving the detecting members and removable part into cooperation with each other subsequent to separation of the detecting members from the printing devices.

4. In a printing machine, a platen, means se-

- 5 sequentially moving printing devices relative to the platen, said printing devices having identifying means thereon, a selector mechanism for controlling operation of the platen and including detecting members movable into engagement with said identifying means, a removable part cooperating with said detecting members after separation thereof from the identifying means and determining the operation of the selector mechanism.
- 10 5. In a printing machine, a platen, means sequentially moving printing devices relative to the platen, said printing devices having identifying means thereon, a selector mechanism for controlling operation of the platen and including detecting members movable into engagement with said identifying means, a removable part cooperating with said detecting members, and means for separating said detecting members and said removable part and for moving said detecting members into engagement with said identifying means and for then moving the detecting members and the removable part into cooperation with each other subsequent to the separation of the detecting members from the identifying means.
- 15 6. In a printing machine embodying a platen and means sequentially moving printing devices relative to the platen, the combination of a selector mechanism including a removable part and detecting means cooperating with said removable part and said printing device, means for controlling operation of the platen, and an arm for moving said detecting means toward and from the printing devices and adapted to be positioned by the selector mechanism to control the operation of the platen.
- 20 7. In a printing machine, means sequentially moving printing devices through the machine, the combination of a selector mechanism including a support, detecting means on said support and adapted for cooperation with the printing devices, a head movable relative to said detecting means, and a removable part carried by said head for cooperation with said detecting means after separation thereof from the printing devices to determine the position of said head relative to said support.
- 25 8. In a printing machine, means sequentially moving printing devices through the machine, the combination of a selector mechanism including a support, detecting means on said support and adapted for cooperation with the printing devices, a head carried by said support, a removable part in said head, and means acting on said head for urging said removable part toward said detecting means whereby said head is positioned by cooperation of said removable part and said detecting means after separation of said members from the printing devices.
- 30 9. In a printing machine, means sequentially moving printing devices through the machine, the combination of a selector mechanism including a support, detecting means on said support and adapted for cooperation with the printing devices, a head movable relative to said detecting means, a removable part carried by said head for cooperation with said detecting means for determining the position of said head relative to said support, and means for moving said support to engage said detecting means with a printing device to set said detecting means to determine the cooperation thereof with the head after separation of the detecting means from the printing devices.
- 35 10. In a printing machine, means sequentially moving printing devices through the machine, the combination of a selector mechanism including a support, a plurality of detecting fingers carried by the support and adapted for cooperation with the printing devices, a head carried by said support, a removable part in said head, means acting on said head and urging said removable part toward said detecting fingers, and means for moving said support to engage said detecting fingers with a printing device to set said fingers in a certain manner whereby said set fingers cooperate with said removable part to determine the position of said head after separation of the fingers from the printing devices.
- 40 11. In a printing machine, means sequentially moving printing devices through the machine, the combination of a selector mechanism including a support, a plurality of detecting fingers carried by the support and adapted for cooperation with the printing devices, a head carried by the support, a matrix carried by the head for cooperation with the fingers, means urging the matrix toward the fingers, and means for separating the fingers and matrix and for engaging the fingers with a printing device and for then moving the fingers and matrix into cooperation with each other to determine the position of said head after separation of the fingers from the printing devices.
- 45 12. In a printing machine, means sequentially moving printing devices having identifying means thereon through the machine, the combination of a selector mechanism including a support, a plurality of detecting fingers carried by the support and adapted for cooperation with the printing devices, a head carried by the support, a matrix carried by the head for cooperation with the fingers, means urging the matrix toward the fingers, means for separating the fingers and matrix, means for engaging the fingers with the identifying means on a printing device to set the fingers in a certain manner, and means for moving the set fingers and the matrix into cooperation to determine the position of said head after separation of the fingers from the printing devices.
- 50 13. In a printing machine, a platen, means sequentially moving printing devices relative to the platen, the combination of a selector mechanism including a support, a plurality of detecting fingers carried by the support, a head carried by the support, a matrix carried by the head for cooperation with the fingers, means for urging the matrix toward the fingers, means for separating the fingers and matrix, means for engaging the fingers with selection indicating means on a printing device to set the fingers in a certain manner, means for moving the set fingers and the matrix into cooperation to determine the position of said head, means for holding the fingers in their set condition after disengagement thereof from the selection indicating means on the printing device and prior to engagement thereof with the matrix, means controlled by the position of the head for controlling the operation of the platen, and variable means on said head for varying the operation of the platen controlling means.
- 55 14. In a printing machine embodying a platen and means sequentially moving printing devices relative to the platen, the combination of a selector mechanism including a removable part and detecting means cooperating with said removable part, and adapted to be engaged with identifying means on the printing device to be set up,

- means for holding the detecting means in set-up condition during movement of the detecting means from engagement with the identifying means on the printing devices until engagement 5 thereof with said removable part, means operated by said selector mechanism for controlling the operation of the platen, and means for varying the operation of the means operated by said selector mechanism.
- 10 15. In a printing machine, a platen, means sequentially moving printing devices relative to the platen, said printing devices having selection indicating means thereon, a selector mechanism including detecting means movable into engagement with said selection indicating means, a removable part cooperating with said detecting means, said detecting means being positioned in a variable manner upon engagement thereof with the selection indicating means on the printing 10 devices, and means for retaining the detecting means so positioned after disengagement thereof from the selection indicating means and prior to engagement thereof with the removable part, means for controlling the operation of the platen 20 regulated by the cooperation of the detecting means and the removable part, and means for reversing the operation of the platen operation controlling means.
- 25 16. In a printing machine embodying means sequentially moving printing devices therethrough, the combination of a selector mechanism including relatively movable parts, detecting members mounted on one of said parts, a control member removably mounted on the other of said parts and having sections projecting from one face thereof adapted for cooperation with said detecting members under predetermined conditions, and a signal operable by said selector mechanism upon cooperation of said detecting 30 members with said sections.
- 35 17. In a printing machine embodying means sequentially moving printing devices therethrough, the combination of a selector mechanism including relatively movable parts, detecting members mounted on one of said parts, a removable member in the other of said parts and adapted for cooperation with said detecting members, a signal, and means on said removable member for effecting operation of said signal upon operation of said selector mechanism in a predetermined manner as determined by the cooperation 40 of said detecting members with said removable member.
- 45 18. In a printing machine sequentially moving printing devices therethrough, the combination therewith of a selector mechanism including relatively movable parts, detecting members mounted on one of said parts, a control member removably mounted on the other of said parts and having open and closed portions adapted for cooperation with said detecting members, certain of said closed portions including sections projecting beyond one face of said control member and adapted for cooperation with said detecting members under predetermined conditions, means controlled by said selector when said detecting members cooperate with the open and closed portions of said control member in a predetermined manner, and a signal operable by said selector mechanism upon cooperation of said detecting members with said sections.
- 55 19. In a printing machine, means sequentially moving printing devices having identifying means thereon through the machine, a selector mechanism including detecting members mov-
- able into engagement with the identifying means, a removable part cooperating with said detecting members, means for operating said detecting members and said removable part and for moving said detecting members into engagement with said identifying means and for then moving the detecting members and removable part into cooperation with each other, a signal, and means on the removable part for effecting operation of said signal upon cooperation of said detecting members and said removable part in a predetermined manner determined by the means on said removable part.
- 60 20. In a printing machine embodying a platen and means sequentially moving printing devices relative to the platen, the combination of a selector mechanism including a removable part and detecting means cooperating with said removable part, means operated by said selector mechanism for controlling the operation of the platen, and means for rendering said selector mechanism inoperative during multiple operations of the platen on a printing device.
- 65 21. In a printing machine embodying a platen and means sequentially moving printing devices relative to the platen, the combination of a selector mechanism including a removable part and detecting means cooperating with said removable part, means operated by said selector mechanism for controlling the operation of the platen, and means for rendering the printing device moving means and the selector mechanism inoperative during multiple operations of the platen on a printing device.
- 70 22. In a selector, relatively movable parts, detecting members on one of said parts and movable into a detecting position, and a removable member on the other of said parts and adapted for cooperation with said detecting members after movement thereof from detecting position to determine the operation of the selector.
- 75 23. In a selector, relatively movable parts, detecting members pivotally mounted on one of said parts and movable into a detecting position, a member removably mounted in the other of said parts and adapted for cooperation with corresponding ends of said detecting members after movement thereof from detecting position to determine the operation of the selector.
- 80 24. In a selector adapted for use in a printing machine through which printing devices having identifying means thereon are sequentially passed, relatively movable parts, detecting members on one of said parts and adapted to be disposed in predetermined positions by cooperation thereof with the identifying means on the printing devices, a member removably mounted in the other of said parts and adapted for cooperation with said detecting members after arrangement thereof in said predetermined positions and separation thereof from the printing devices to determine the functioning of the selector mechanism.
- 85 25. In a selector adapted for use in a printing machine through which printing devices having identifying means thereon are sequentially passed, relatively movable parts, detecting members pivotally mounted on one of said parts and having corresponding ends thereof adapted for cooperation with the identifying means on the printing devices to arrange the opposite ends thereof in predetermined positions, and a member having predetermined characteristics removably mounted in the other of said parts and adapted for cooperation with said opposite ends.

of said detecting members after separation thereof from the identifying means to determine the functioning of said selector mechanism.

26. In a selector adapted for use in a printing machine through which printing devices having identifying means thereon are sequentially passed, relatively movable parts, detecting members pivotally mounted on one of said parts and having corresponding ends thereof adapted for cooperation with the identifying means on the printing devices to arrange the opposite ends thereof in predetermined positions, a member having predetermined characteristics removably mounted in the other of said parts and adapted for cooperation with said opposite ends of said detecting members to determine the functioning of said selector mechanism, and means on the part carrying the removably mounted member and adapted to retain said detecting members in said predetermined positions to insure accurate cooperation thereof with said member having predetermined characteristics.

27. In a selector, relatively movable parts, detecting members on one of said parts, a removable member on the other of said parts and adapted for cooperation with said detecting members to determine the operation of said selector, and means on the part carrying the removably mounted member and adapted to retain said detecting members in position to insure accurate cooperation of said removable part therewith.

28. In a selector, relatively movable parts, detecting members pivotally mounted on one of said parts, a member removably mounted in the other of said parts and adapted for cooperation with corresponding ends of said detecting members, and means on the part carrying the removably mounted member and adapted to hold said corresponding ends of said detecting members in position after pivoting thereof and during cooperation thereof with the removably mounted member.

29. In a printing machine, means sequentially moving printing devices through the machine, the combination of a selector mechanism including a support, detecting members on said support and adapted for cooperation with the printing devices, a head movable relative to said detecting members, a removable part carried by said head for direct cooperation with said detecting members to determine the position of said head relative to said support, and means on said head for insuring accurate cooperation of said detecting members with said removable part.

30. In a printing machine, means sequentially moving printing devices having identifying means thereon through the machine, the combination of a selector mechanism including a support, a plurality of detecting fingers carried by the support and adapted for cooperation with the identifying means on the printing devices, a head carried by the support, a matrix carried by the head for cooperation with the fingers, means urging the matrix toward the fingers, means for operating the fingers and matrix, means for engaging the fingers with the identifying means on a printing device to set the fingers in a predetermined manner, means for moving the set fingers and the matrix to determine the position of said head, and means on said head for retaining the fingers in their set position to insure accurate cooperation thereof with the matrix.

31. In a printing machine, means sequentially moving printing devices having identifying means thereon through the machine, a selector mecha-

nism including detecting members movable into engagement with the identifying means, a removable part cooperating with said detecting members, means for separating said detecting members and said removable part and moving said detecting members into engagement with the identifying means and for then moving the detecting members and the removable part into cooperation with each other, and means engaging said detecting members to retain them in positions into which they are moved by cooperation thereof with said identifying means, said last-named means functioning during movement of the detecting members and removable part into cooperation with each other and during cooperation of said members and part with each other.

32. In a selector, relatively movable parts, detecting members on one of said parts, a removable member on the other of said parts and adapted for cooperation with said detecting members to determine the relative position of the part carrying the removable member, and means for determining the final position of said part carrying said removable member.

33. In a selector, relatively movable parts, detecting members on one of said parts, a removable member on the other of said parts and adapted for cooperation with said detecting members to determine the relative position of the part carrying the removable member, and control means including a positioning member adapted for cooperation with the part carrying said removable member to determine the final position of said part.

34. In a selector, relatively movable parts, detecting members on one of said parts, a removable member on the other of said parts and adapted for cooperation with said detecting members to determine the relative position of the part carrying the removable member, and control means including a positioning member and a settable member and wherein the operation of the settable member is determined by the cooperation of the part carrying the removable member with said positioning member.

35. In a printing machine, a selector mechanism including a movable support, a plurality of detecting fingers carried by the support, a head mounted on the support, a matrix carried by the head for cooperation with the detecting fingers and adapted to determine the position of the head relative to the support, and means cooperating with the head for determining the position of the support in accordance with the relative position of the head with the support.

36. In a printing machine, means sequentially moving printing devices having identifying means thereon through the machine, the combination of a selector mechanism including a support, a plurality of detecting fingers carried by the support and adapted for cooperation with the identifying means, a head mounted on the support and movable relative thereto, a matrix carried by the head and adapted for cooperation with the fingers, means urging the matrix toward the fingers, means separating the fingers and the matrix, means engaging the fingers with the identifying means to set the fingers in a determined manner, means moving the set fingers and matrix into cooperation to determine the position of the head relative to the support, a positioning member, and means carried by the head and cooperating with the positioning member for determining the position of the movable

support in accordance with the position of the head relative to the support.

37. In a printing machine, printing means, means for sequentially moving printing devices through said machine past said printing means, selector means for controlling the operation of said printing means whereby impressions will be made only from determined of the printing devices, and means for reversing the operation of said selector means whereby impressions will be made from printing devices other than those determined by the operation of said selector means before the reversing thereof and including a member having a notch therein and seating portions adjacent said notch and a member adapted to be seated normally either in said notch or on a seating portion as determined by the set-up of the reversing means.

38. In a printing machine including means sequentially moving printing devices having identifying means thereon through the machine, a controllable device, a selector mechanism adapted to control said device and including an arm having detecting means at one end thereof, means for moving said detecting means to and from cooperation with the identifying means on said printing devices, and means cooperating with said detecting means for positioning said arm to thereby control said device in accordance with the positioning of said detecting means as determined by the cooperation thereof with said identifying means.

39. In a printing machine including means sequentially moving printing devices having identifying means thereon through the machine, a controllable device, a selector mechanism adapted to control said device and including an arm having detecting means at one end thereof, said detecting means including relatively movable parts and having detecting fingers on one of said parts adapted to cooperate with the identifying means on the printing devices and having means on the other part adapted for cooperation with said detecting fingers to be positioned thereby subsequent to engagement thereof with the identifying means on the printing devices, and means cooperating with the positioned part of said detecting means for positioning said arm to thereby control said device in accordance with the positioning of said detecting means as determined by the cooperation thereof with the identifying means.

40. In a printing machine, a platen, means sequentially moving printing devices relative to the platen, the combination of a selector mechanism including a support, a plurality of detecting fingers carried by the support, a head carried by the support, a matrix carried by the head for cooperation with the fingers, means for urging the matrix toward the fingers, means for separating the fingers and matrix, means for engaging the fingers with selection indicating means on a printing device to set the fingers in a certain manner, means for moving the set fingers and the matrix into cooperation to determine the position of said head, means for holding the fingers in their set condition after disengagement thereof from the selection indicating means on the printing device and prior to engagement thereof with the matrix, and means controlled by the position of the head for controlling the operation of the platen.

41. In a printing machine embodying a platen and means sequentially moving printing devices relative to the platen, the combination of a se-

lector mechanism including a removable part and detecting means cooperating with said removable part and adapted to be engaged with identifying means on the printing device to be set up, means for holding the detecting means in set-up condition during movement of the detecting means from engagement with the identifying means on the printing devices until engagement thereof with said removable part, and means operated by said selector mechanism for controlling the operation of the platen.

42. In a printing machine, a platen, means sequentially moving printing devices relative to the platen, said printing devices having selection indicating means thereon, a selector mechanism including detecting means movable into engagement with said selection indicating means, a removable part cooperating with said detecting means, said detecting means being positioned in a variable manner upon engagement thereof with the selection indicating means on the printing devices, means for retaining the detecting means so positioned after disengagement thereof from the selection indicating means and prior to engagement thereof with the removable part, and means for controlling the operation of the platen regulated by the cooperation of the detecting means and the removable part.

43. In a printing machine embodying a platen and means sequentially moving printing devices relative to the platen, the combination of a selector mechanism including a removable part and detecting means cooperating with said removable part and said printing devices, means for controlling operation of the platen, an arm for moving said detecting means toward and from the printing devices and adapted to be positioned to control the operation of the platen, and means for operating said arm to move the detecting means toward the printing devices and adapted to disengage said arm subsequent to movement of the detecting means away from the printing devices and into cooperation with the removable part to enable said arm to be positioned to control the operation of the platen.

44. In a printing machine embodying a platen and means sequentially moving printing devices relative to the platen, the combination of a selector mechanism including a removable part and detecting means cooperating with said removable part and said printing devices, means for controlling operation of the platen, an arm for moving said detecting means toward and from the printing devices and adapted to be positioned to control the operation of the platen, and means for moving said removable part relative to said detecting means and independent of the movement thereof imparted to the detecting means by said arm.

45. In a printing machine embodying a platen and means sequentially moving printing devices relative to the platen, the combination of a selector mechanism including a removable part and detecting means cooperating with said removable part and said printing devices, means for controlling operation of the platen, an arm for moving said detecting means toward and from the printing devices and adapted to be positioned to control the operation of the platen, means for operating said arm to move the detecting means toward the printing devices and adapted to disengage said arm subsequent to movement of the detecting means away from the printing devices and into cooperation with the removable part to enable said arm to be posi-

tioned to control the operation of the platen, and means for moving said removable part relative to said detecting means and independent of the movement thereof imparted to the detecting means by said arm.

5 46. In a selector, relatively movable parts, detecting members on one of said parts and movable into detecting position, a removable member on the other of said parts and adapted for cooperation with said detecting members after movement thereof from detecting position to determine the operation of the selector, and an arm for moving the detecting members into and from detecting position and adapted to be positioned by the cooperation of the detecting members with the removable member after movement of the detecting members from detecting position.

10 47. In a selector, relatively movable parts, detecting members on one of said parts and movable into detecting position, a removable member on the other of said parts and adapted for cooperation with said detecting members after movement thereof from detecting position to determine the operation of the selector, and means for moving said removable part relative to said detecting members and independent of the movement of the detecting members into and from detecting position.

15 48. In a selector, relatively movable parts, detecting members on one of said parts and movable into detecting position, a removable member on the other of said parts and adapted for cooperation with said detecting members after movement thereof from detecting position to determine the operation of the selector, an arm for moving the detecting members into and from detecting position and adapted to be positioned by the cooperation of the detecting members with the removable member after movement of the detecting members from detecting position, and means for moving said removable part relative to said detecting members and independent of the movement of the detecting members into and from detecting position.

20 49. In a selector, an arm mounted for pivotal movement, detecting members mounted on said

25 arm, a head having a selection determining member therein and mounted on said arm for movement relative to said detecting members, means for imparting pivotal movement to said arm to move said detecting members into and from detecting position, means for moving said head to effect separation of said selection determining member from said detecting members upon movement of said detecting members into detecting position and to effect engagement of said selection determining member with said detecting members upon movement of said detecting members from detecting position, positionable means on said head and adapted to be disposed in varied positions as selected by the cooperation of 15 said selection determining member with said detecting members, and means engageable with said positionable means to determine the operation of said selector.

30 50. In a selector, an arm mounted for pivotal movement, detecting members mounted on said arm, a head having a selection determining member therein and mounted on said arm for movement therewith and for movement relative to said detecting members, means for imparting 25 pivotal movement to said arm to move said detecting members into and from detecting position and to simultaneously move said head to and from set-up position, means for moving said head to effect separation of said selection determining member from said detecting members upon movement of said detecting members into detecting position and to effect engagement of said selection determining member with said detecting members upon movement of said detecting members from detecting position, positionable means on said head and adapted to be disposed in varied positions as selected by the cooperation of 35 said selection determining member with said detecting members, and means engageable with said positionable means to determine the set-up position of said head to thereby 40 position said arm to determine the operation of said selector.
